Attys.

UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

RAILWAY-CAR-TRUCK ARRANGEMENT.

Application filed February 12, 1923. Serial No. 618,683.

To all whom it may concern:

Be it known that I, GEORGE G. FLOYD, a citizen of the United States, residing at Chicago, in the county of Cook and State 6 of Illinois, have invented certain new and useful Improvements in Railway-Car-Truck Arrangements, of which the following is a specification.

This invention relates to a railway car 10 truck arrangement.

As is well known in the art, that portion of the tension member between the bolster columns is subjected to bending stresses in addition to tension stresses. Consistent 15 with other features of design, the distance between the bolster columns, accordingly, should be reduced as much as possible. In cases in which it is desired to increase the spring capacity, with all springs being located between the bolster columns, some 20 special arrangement preferably is used for maintaining the distance between the bolster columns as a minimum.

One object of the invention is to provide 25 a simple truck arrangement in which the spring capacity is increased, while at the same time the distance between the bolster columns and also the wheel base is minimized, the side frame made of maximum 30 strength and minimum weight, and ample brake clearance is provided.

Another object is to provide a simple and efficient truck of high spring capacity adapted to meet the various requirements 35 under service conditions.

These and other objects are accomplished by means of the arrangement shown on the accompanying sheet of drawings, in which—

Figure 1 is a fragmentary side elevation 40 of a railway car truck, parts being in section, embodying my invention;

Figure 2 is a fragmentary top plan view of the same arrangement; and

Figures 3 and 4, respectively, are sectional views taken in the planes of lines 45 3—3 and 4—4 of Figure 1.

The various novel features of the invention will be apparent from the following description and drawings and will be particularly pointed out in the appended 50 claims.

Referring to the figures of the drawing, it will be noted that my invention is illustrated in connection with a railway car 55 truck including a side frame 10 in which, in

this particular instance, although not necessarily so, the tension member 11, compression member 12 and bolster columns 13 are all integrally formed.

As is well known, four springs associated 60 with each side frame are usually employed for supporting the bolster and the load imposed thereon, all of said four springs being seated at each end of the spring plank. In this particular instance, it is desired to employ more than four springs; six are shown. Two centrally arranged springs 14 are seated upon the outer end of the channel or central portion of a spring plank 15, which spans the side frames and is supported 70 directly or indirectly upon the tension member 11 between the bolster columns 13. For holding the spring plank in position it will be noted that the upper surface of the tension member is provided with two upstanding dowels 16 which are received in associated openings 17 in the spring plank. These dowels 16 also project above the spring plank within the interior of the coiled springs 14 for preventing the latter 80 from being dislocated.

In this truck of increased spring capacity there are two springs 18 at each side of the centrally arranged springs 14. To minimize the distance between the bolster columns and to overcome the necessity of weakening the side frame or altering the general contour thereof, the four end springs 18 are elevated with respect to the central springs 14. More strictly speaking, the 90 four end springs 18 are mounted upon elevated spring seats 19, one spring seat 19 serving for two springs 18 at one side of the central springs 14 and the other elevated spring seat 19 serving for the other 95 two end springs 18 on the other side of said central springs 14. Each of the elevated spring seats 19 is separate from each other and separate from the tension member, but supported upon the latter. Each 100 spring seat 19 is provided with dowel pins 20, which are received by corresponding openings 21 in the tension member for definitely locating said spring seats. Aside from the dowel pins 20, the underside of 105 each spring seat 19 is angled with respect to the top of the spring seat to conform to the angle of the tension member at that point. The elevated spring seats 19 are provided with additional dowel pins 22 110

which project through associated openings 23 in raised shelf-like portions 24 of the spring plank 15, which shelf-like portions extend over and rest upon the elevated 5 spring seats 19. The dowel pins 22 extend upwardly beyond the spring seat shelves 24 and within the coiled springs 18 for co-operating to prevent displacement of said springs.

10. By referring particularly to Figure 1 it will be noted that the spring plank has a relatively narrow channel shaped central portion which rests directly upon the tension member 11 between the elevated spring 15 seats 19, the shelf portions 24 extending outwardly from the upper edges of the flanges 25 of the spring plank.

A stepped bolster 26 is provided which rests upon the springs 14 and 18, the bolster 20 being stepped to accommodate said springs which are of the same length but some of which are elevated with respect to others.

By thus providing the combination herein disclosed the objects of the invention 25 are obtained.

It is my intention to cover all modifications of the invention falling within the spirit and scope of the following claims.

I claim:

30. 1. In a railway car truck, the combination of a side frame including tension and compression members and bolster columns, bolster spring supporting seats, one of which is on a higher level than a certain one of 35 the other seats and is separate from said other spring seat and separate from said tension member and mounted on the latter, and a spring plank having portions supported on said tension member and said 40 elevated spring seat, and springs resting upon said spring plank, whereby an in-

creased number of standard springs may be located between bolster columns spaced apart a given distance.

2. In a railway car truck, the combination of a side frame including tension and compression members and bolster columns, a spring plank supported by said tension member intermediate said bolster columns and having portions at different levels upon 45 which bolster supporting springs may rest, and separate elevated spring supporting members separate from said spring plank and separate from said tension member supported upon the latter and being located 50 under the elevated portions of the spring plank for co-operating to support the latter and certain springs whereby an increased number of standard springs may be located 55 between bolster columns spaced apart a given distance.

3. In a railway car truck, the combination of a side frame including tension and compression members and bolster columns, a channel shaped spring plank having laterally extending shelf portions at a higher level than the web of the channel portions, separate members separate from said spring plank and separate from said tension member 60 and resting upon the latter, interposed 65 between said tension member and the elevated shelf portions of said spring plank for supporting the latter, and bolster supporting springs mounted within the channel portion of the spring plank and on the elevated shelf portions thereof whereby an increased number of standard springs may be located 70 between bolster columns spaced apart a given distance.

Signed at Chicago, Illinois, this 9th day 75 of February, 1923.

GEORGE G. FLOYD.
